Original application January 2, 1940, Serial No.
 312,012. Divided and this application August
 24, 1940, Serial No. 354,021

19 Claims. (Cl. 164—114)

This invention relates to improvements in recording apparatus, and more particularly to an improved coin recording apparatus suitable for embodiment in a fare box for use on street railways, buses and the like.

The present application is a division of my application for Letters Patent on Coin handling and totaling devices, filed January 2, 1940, and bearing Serial No. 312,012.

Many fare box assemblies heretofore prevalent employed for the purpose noted indicate only by visible record, the totals of coils of different denominations deposited by fare-paying passengers. These totals are not, as a rule, reset at the end of a run or day, and so require each car conductor or crew to transcribe the totals at the beginning and end of the run, wherefrom is derived, by difference, the trip totals. This prevailing procedure is markedly unsatisfactory for a number of reasons, among which may be noted the requirement of calculations to arrive at trip totals or per-man totals, and the consequent high degree to which the personal equation enters into the accuracy of fare tabulation. Accordingly, a general objective of the present invention is to eliminate the noted prevailing difficulties, by the provision of an improved and greatly simplified coin-responsive recording apparatus adapted to provide an accurate and unalterable record of coin totals.

A further general object of the invention is attained in an improved coin-recording apparatus which is well adapted for use in fare boxes, to augment with great advantage, the trip and total registers which provide only for visible records of the coin and token input to the box, the present recorder device being adapted for the production of a permanent record of coin and token totals, whereby the conductor is relieved of any necessity of determining by calculation of any form, the results of his trip or day's run.

Another object of the invention is to provide an improved coin-responsive recording device which may be operated at will, to produce a permanent record of the coin totals accumulated by the recorder, and wherein following such record-producing operation, the recorder mechanism is automatically reset or cleared of the coin totals accumulated thereby.

A further object resides in the provision of an improved recording mechanism which is susceptible of use in coin handling apparatus generally, and in such apparatus which may or may not include visual indicating coin registering means, or which may be employed as an independent

recording mechanism, with or without minor changes from the construction disclosed, in apparatus other than fare box devices, which may require such recorder means.

5 The foregoing objects and many others will appear readily from the following description of preferred embodiment of my improved recorder apparatus, as considered in view of the accompanying drawings wherein the recorder is illustrated as applied to a fare box assembly provided for handling coins, tokens and the like.

In the drawings, Fig. 1 is a vertical sectional elevation taken through a fare box, illustrating elements of the recorder; Fig. 2 is a vertical sectional elevation through the fare box, as taken in a plane transverse to that of Fig. 1, and illustrating operating parts of the recorder; Fig. 3 is a vertical sectional elevation of the box, as taken in a plane transverse to that of Fig. 2 and 10 as viewed from line 3—3 of Fig. 2; Fig. 4 is a fragmentary vertical section through a portion of the device, as viewed from line 4—4 of Fig. 2, and illustrating certain of the elements for recording the fares passing through the device;

15 Fig. 5 is a view in perspective and somewhat enlarged, of a record card punching element utilized in the recording mechanism; Fig. 6 is a fragmentary horizontal section through the box assembly, as viewed along line 6—6 of Fig. 2,

20 and showing elements of the recorder mechanism; Fig. 7 is a fragmentary vertical section through the recorder mechanism of Fig. 6, as viewed from line 7—7 thereof; Fig. 8 is a similar fragmentary section, as viewed along line 8—8

25 of Fig. 6; Fig. 9 is an elevation of one face of a card adapted to be utilized for recording the totals accumulated in the recorder; Fig. 10 is a fragmentary vertical section through the fare box, as viewed along line 10—10 of Fig. 3, and illustrating actuating means for the recorder resetting mechanism; Fig. 11 is an enlarged, frag-

30 mentary elevation, partly in section, of a part of the recorder mechanism, illustrating an accumulator or odometer type of drive for certain elements thereof; Fig. 12 is an enlarged, frag-

35 mentary vertical section of a portion of the recorder mechanism, illustrating camming means for actuating certain parts of the recorder; Fig. 13 is a fragmentary vertical section of the recorder mechanism, the view being similar to that of Fig. 4, but illustrating certain modifications in the mechanism to adapt the same for printing the totals accumulated in the device, upon a record card; Fig. 14 illustrates in enlarged perspective,

40 45 50 55 55 a printing die utilized in the modified recorder of

Fig. 13, the element here shown being similar to the punch of Fig. 5, but bearing on its contact face a raised numeral or other character, as the numeral 2, shown; Fig. 15 is a fragmentary vertical section through a portion of the recorder mechanism, the view illustrating certain modifications therein and additional apparatus operated by the recorder, for producing a printed record of certain totals accumulated by the recorder; Fig. 16 is a fragmentary horizontal section through the modified device of Fig. 15, as taken along line 16-16 thereof, Figs. 17 and 18 are fragmentary vertical detail sections of the modified recorder, as taken respectively, along line 17-17 and 18-18 of Fig. 15, and Fig. 19 is an elevation of one face of a card adapted to be utilized in connection with the modified recorder of Fig. 15, for recording the totals accumulated in the device.

As exemplifying the applicability of my improved recorder apparatus, it is illustrated in the drawings as embodied in a fare box assembly of a type adapted for receiving, sorting and registering coins, tokens and the like. By adding the present recorder device, the function and utility of the fare box is thereby augmented, to the end of providing for the production of an accurate and permanent record of the total coin or fares handled by the box. While the presently improved recorder may be utilized in any apparatus requiring recording means of this character, it is particularly suited for incorporation in a fare box mechanism of the form and construction fully disclosed in my application Serial No. 312,012, hereinbefore noted, and of which the present application is a division. In the present example, the recorder is shown as embodied in a fare box constructed according to the disclosure in the application referred to, so that reference may be had to such application for a complete understanding of the fare box mechanism and those parts thereof with which the present recorder mechanism is operatively associated, and which appear in the drawing disclosure of the present application. Accordingly, apart from the recorder mechanism, a brief reference only, will be made wherever necessary or desirable herein, to the parts of the fare box assembly shown, as for example, to the token counters 274, 275, the per-man cash counter 273, the transfer counters 276 and 277, and to certain of the counter operating parts and related elements, as such may be related to the improved recorder device.

To the end of providing a permanent record, produced in a manner entirely free of the personal equation, of the per-man or trip totals, accumulated in the farebox, it is preferred to utilize a form card punched or printed, say at the end of a run. The agencies employed for this purpose consist, preferably, of a plurality of groups of punch or printing elements so located in respect to a card holder in the casing, that when the card is punched or printed at the end of a run, the perforations produced by the punches will coat with definitely located legends on a record card to provide the desired readings. Although the individual recording elements are hereinafter referred to as punches, it will be understood that each thereof may be provided with a numeral or other character, and serve as a stamping or printing die, instead of a perforating punch, the essential result being the production of a permanent record.

In the present exemplary disclosure, the card punching units employed correspond in actuation

and reading, to the several per man counters, that is to say one punching unit provided to record the total visibly registered on the small token counter 274; another corresponding to the large token counter 275; still another providing a record of the reading of the per-man cash counter 273, and further, a pair thereof effecting a record of the readings of the transfer counters 276 and 277. Yet another punching unit is employed to provide a record of certain facts incident to the use of a given fare box, as this will later appear. The six punch assemblies thus provided according to the present disclosure, are indicated generally (Figs. 1 and 2) at 400, for per-man cash; 401 for recording transfers, 402 for small tokens, 403 for transfers; 404 for large tokens, and 405 for recording data later to be indicated. Referring particularly to Fig. 3, the punch units 400, 402 and 404 are actuated respectively, from the cash and token counter drive shafts 292, 316 and 332, as by respective bevelled pinions 406, 406B and 406D secured to the shafts, and which enmesh respectively, with bevelled drive pinions 407, 407B and 407D for the units 400, 402 and 404. The counter drive shafts 292, 316 and 332 as utilized according to the present example, to operate the recorder mechanism for setting up the cash and token record producing elements thereof, as this will hereinafter more fully appear, are operated through mechanism (shown in the parent case, Serial No. 312,012, above referred to) actuated in response to the coins and tokens received in the fare box. Further, since the single shaft 292 is employed to operate the cash punch assembly or unit 400 of the present recorder mechanism, which unit provides for the production of a record of the cash total of all coins handled by the fare box, the coin-responsive actuating mechanism for the shaft 292 necessarily must be of a character which will produce rotation of the shaft in proportion to the several denominations of coins handled. Although any suitable coin-singling and denomination-determining means may be employed for this purpose, reference is directed to my application Serial No. 312,012, hereinbefore noted, which fully discloses improved coin and token singling and denomination-determining apparatus, and counter-actuating means operated thereby, in operating relation to the counter drive shafts 292, 316 and 332. Thus for the purposes of the present exemplary disclosure, the shaft 292 may be referred to in the following description of the recorder mechanism, as well as in the claims hereunto appended, as a coin-controlled or coin-responsive operating shaft for the cash recorder unit of the device, while the shafts 316 and 332 may be referred to in a similar manner, as coin-controlled or coin-responsive operating shafts for the associated token recorder units of the device. It is understood, of course, that the word "coin" as employed above in connection with shafts 316 and 332, includes metal tokens or other token elements employed as fares, in lieu of established monetary units or cash.

With respect to the transfer punch units, the unit 401 is driven from the transfer counter assembly 277, as by a drive connection which includes as shown by Fig. 3, a counter gear 382 enmeshing with a gear 383 on a stub shaft 384 journaled in a bracket 385. Also connected to shaft 384 is a bevelled pinion 386 which enmeshes with a similar bevelled pinion 387 on the upper end of a vertical shaft 388. A bevelled pinion 389 carried by the lower end of shaft 388, enmeshes

with a bevelled pinion 390 on a shaft element 391 journalled in a bracket 392. A bevelled pinion 406A which in the example shown, may be formed as a unit with the pinion 390, in turn enmeshes with a bevelled drive pinion 407A of the recorder unit 401. In a similar manner the transfer punch unit 403 is driven from the transfer counter assembly 276, the elements of the drive corresponding to those of the drive from the counter 271 and being designated by the same reference numerals, but differentiated by letter suffixes.

As best appears in Figs. 3 and 10, actuation of the drive pinion 407E for the punch unit 405, is effected from and in response to return movement of a recorder control and reset hand lever 360, this same lever also being utilized as fully disclosed by my application Serial No. 312,012, noted hereinbefore, for effecting the resetting of per man counter assemblies 273—277. Accordingly, the lever operated member 362 is provided with a finger portion 408 projecting oppositely to the plate portion providing the gear-segment 363, which serves a purpose later to appear, the finger supporting a pin 409 adapted for camming-engagement with an angulate operating face 410 on the upper end of a vertically extending lever 411. The lever is pivotally mounted at its lower end, to the fare box housing wall 32, as at 412, and is urged against a stop 413 by a spring 414. A pawl 415 pivotally carried by the lever 411, is spring-urged into engagement with a ratchet wheel 416 secured upon a horizontal stub shaft 417. The shaft 417 is journalled in the housing wall 32 and in the frame wall 368, and has secured to its inner end, a bevelled pinion 406E which enmeshes with the bevelled drive pinion 407E of the recorder unit 405. Thus, upon depression of the hand lever 360, the finger-carried pin 409 will engage the face 410 of lever 411, and therethrough, to pivot the lever away from its stop 413, as to the left in Fig. 10. As a result thereof, the pawl 415 will be re-engaged with one of the ratchet teeth on wheel 416, so that upon a release of the hand lever 360, the finger-pin 409 will be released from the lever 411, to permit the spring 414 to return the lever against its stop 413. The return movement of lever 411 results in rotation of the ratchet wheel 416, as effected through the pawl 415, the arrangement being such that the wheel is thereby rotated a distance of one tooth, or as in the present example, through one-tenth of a revolution since there are ten teeth on the ratchet. Thus the shaft 417 is driven by the wheel 416, will be rotated through one-tenth of a revolution, and through the shaft pinion 406E enmeshing with the drive pinion 407E of the recorder unit 405, will serve thereby, to cause a one-tenth revolution of the latter pinion.

Referring now to a description of the individual recording assemblies, since the construction of each thereof is, or may be, identical except for the number of rotatable and punch elements employed, the largest such unit, viz., 400 will be described by reference to its several parts, and the corresponding parts of each of the units 401, 402, 403, 404 and 405 will be similarly designated by numerals, but distinguished by different letter suffixes, the parts of unit 401 being differentiated by suffix A, the unit 402 by suffix B, unit 403 by suffix C, unit 404 by suffix D, and unit 405 by suffix E. All of the punching units are assembled in and may be partly or substantially enclosed by a frame structure 418 (Figs. 1, 2 and 6).

Proceeding now with the description of the unit 400, arranged between and journalled in the

lateral walls of the frame 418, is an echelon arrangement of shafts 420, 421, 422, 423 and 424. The shaft 420 is rotated in step-by-step manner by the gear 407 secured thereto outside of the case wall, the gear 407 being driven, as described, by gear 406 and the associated coin-responsive drive shaft 292. Each of the shafts except the last shaft of the series, carries a pinion 425 engaging in appropriate ratio a gear 426, enmeshing in turn with a gear 427 secured to the next parallel shaft in the order of the series, as clearly appears in Fig. 11. The shafts of the series are thus related decimaly after the manner of the counter elements. It has been found expedient to employ pinion elements 425 which may comprise only one or two teeth, so that, as the shaft 420 rotates one revolution, the adjacent shaft 421 will be rotated one-tenth of a revolution, and so through the series of shafts of each unit.

Each of the horizontal shafts 420, 421, etc., carries a drum 428, the drums being uniform throughout the unit in the example disclosed (Figs. 1, 2 and 6). Axially and angularly spaced at even intervals about each drum 428, are a plurality of projections 429, and arranged in spaced planes transversely of the axis of each drum is a series of punches 430, the punches being laterally spaced from each other and each located so as to be engaged by only one of the projections 429. The punches, one of which is shown in perspective elevation by Fig. 5, are supported by and between spaced plate elements 431, the plates being held in spaced relation by and between the opposite, inner frame walls 432 of the frame 418 of the unit. Each punch is characterized by a down turned nose portion 433 which normally overlies the face of the drum in a position for engagement by the projection 429. Each punch may be urged to such initial position by a suitable return spring (not shown in the embodiment presently under description), or as preferred in the instant example, each is free to be returned to its initial position, when not held outwardly by its actuating projection 429, during and as a result of, the card punching or printing actuation of the recorder, as this will appear hereinafter. A plurality of guide pins 434 struck from the plates underlying the several horizontal series of punches (Fig. 1), serve to confine the punches to longitudinal reciprocable movement, as well as to laterally space them. Further, the reciprocable movement of each punch may be limited to the extent required for recording operation thereof, as by an upstanding pin 435 on the adjacent plate, projecting through a longitudinal slot 436 in the punch (Fig. 6). As will appear from Fig. 2, each of the drums 428 is shown as provided with ten of the cams or projections 429, each adapted to register with and engage one of a row or group of ten punches 430. Thus the unit 400, provided with five drums, contains fifty of the punches, and each of the other units shown as embodying three of the drums, contains thirty of the punches.

As shown in Figs. 4, 6 and 8, each of the drum shafts 420, 421, etc., at the drive end, is provided with a ratchet wheel 437 which is engaged by a spring-loaded, pivotal pawl 438. The pawl and ratchet means thus associated with the drum shafts, serve to prevent backward or return movement of the drums in the step-by-step actuation thereof, as will be now appreciated.

The housing frame wall 368 which serves to support the frame 418 of the recorder mechanism, is provided with apertures grouped to re-

ceive and pass the ends of the several punches 430, and to act as guides therefor. These openings are indicated at 439. Spaced slightly outwardly of and parallel to the wall 368, are two plate or wall members 440 and 441 normally relatively spaced and containing punch apertures 442, corresponding in size and location to those designated at 439, the arrangement being such that the punches may each bridge a given pair of openings 442 in the plates. The walls 440 and 441 provide a card pocket or well 443 therebetween, for the reception of a record card as the card 444 of Fig. 9, the card well being of such a size as to position the card with its rows of numerals 445 appropriately disposed with respect to the punch apertures. The plates 440 and 441 are shiftably positioned within the case, as guided by plate-supporting pins 446 secured to frame wall 368, and are spring-retracted to the positions shown in Fig. 4, by coil springs 447 engaging plate 440 and similar springs 448 engaging plate 441 (Figs. 3 and 6).

Actuation of the plates 440 and 441 with a record card 444 placed in the receiving well 443 formed thereby, toward the punch assembly to effect record-punching of the card according to the totals accumulated by the machine, is effected from the hand lever 360 and in response to the depression of the lever, as will presently appear. Secured to or formed as a part of the plate 440, and located on the portion of the plate which is centrally opposite the punch assembly, is a circular flanged member or boss 450 which is centrally apertured, as at 451, to receive and journal therein, the inner end of a shaft 452 (Fig. 12). The opposite end of shaft 452 is journaled in the housing side wall 32, and has operatively secured thereon, a pinion 453 which meshes with a segmental gear 454 provided on the lower end portion 455 of the hand lever actuated plate 362 (Fig. 10), so as to be actuated thereby. Also secured to the shaft 452 is a disc element 456, which has formed near the periphery thereof, a laterally projecting camming element 457. Similarly disposed on the opposing face of the member 450, is a like camming element 458, and as appears in Fig. 12, the mating faces of the cams 457 and 458 bear a diagonal relation to the axis of the shaft 452. The operative arrangement of the mechanism above described, for connecting the hand lever 360 to the plate 440, is such that as the hand lever is depressed the gear 454 on the plate 362, will rotate the shaft 452 through the pinion 453, and thus effect a coaction of the camming surfaces on the elements 457 and 458, to displace the latter and its plate 440 inwardly toward the punch device. As a result, there is effected in sequence, displacement of plate 440 toward plate 441, to position and somewhat compress the record card 444 therebetween, and then displacement of both plates 440 and 441 with the card 444 therebetween, toward the frame wall 368. In the latter step, the displacement of the card as held between the plates 440 and 441, toward the punch assembly, will force the card against the ends of such of the punches 430 as have been actuated to card-punching positions, and so indicating by punch marks in the imprinted legends 445 of the card 444, the desired per-man totals.

Hence it will now appear that, by the initial actuation or depression of lever 360 following the insertion of a card 444 in the card pocket, a permanent record of per-man totals is thereby ef-

fected. It is to be noted here that where the punches 430 of unit 400, punches 403A of unit 401, etc. etc., are not retracted or biased to initial positions by springs or other positive means, as is the case in the present example under description, such thereof which are found in punch-projected positions but not held therein by the drum actuating elements 429, 429A, etc., will be returned as a result of the punching displacement of the card, and without affecting the card. This result is thought to be obvious now, and to require no further explanation.

The arrangement of the drums 428 and projections 429 thereon, is by preference such that one of the projections and an associated punch, corresponds to a zero reading in a given column. The arrangement is further such that, due to the angular spacing of the projections 429 on each drum, no more than one punch of a given row in a given unit or group, is extruded at a given time. This is due to the fact that, as a succeeding punch is actuated, the preceding projection 429 will clear its punch so that at a given time only one punch can be held in an extended or extruded position, by any given drum 428. The same arrangement obtains, of course, in each of the units 401—405.

My preference is to provide one punch in each row corresponding to a zero reading so that, in the event no coins have passed through the machine since the last reset, and a card is punched, a zero reading will be obtained as indicated by punch marks in the zero positions of the several columns of the indicia 445 on the card 444.

In order to insure that the drums 428, 428A, 428B, etc. are each rotated to a definite position so as to cause maximum extension of the punch, and each is definitely retained in such position until moved to the next one, there is provided for each drum in connection with the drum shafts, a ratchet device (Fig. 8), consisting of a spring-loaded pawl 438 engaging a ratchet wheel 437 on the drum shaft, as heretofore described. Thus each drum is releasably retained in each of, say, ten selected positions wherein one of the punches associated therewith, is moved and held outwardly to maximum extent.

It may be noted here that, in the unit 400, the left hand drum (Fig. 1) constitutes a cents counter, the next to the right being readable in ten cent units, thence in order, dollars, ten dollars and one hundred dollar units. In each of the recording punch units 401, 402, 403 and 404, the three drums in order from left to right, are utilized to indicate units, tens and hundreds. With respect to the last or lowermost unit 405 of the recorder mechanism, this unit is actuated in response to the return movement of the hand lever 360, as hereinbefore indicated, so that its punch element or certain of them, will be extruded for card-punching, upon the next or succeeding depression of the hand lever to effect punching of the record card 444. This last punch unit then serves to mark or punch the card 444 in respect to certain data provided on the face of the card, apart from cash and token totals. As indicated on the card 444 (Fig. 9), the "Card No." column thereof will be aligned with the punches of the unit 405, when the card is placed in position, in the recorder well 443. Thus, the arrangement of the unit 405 may be such as to punch a card, as card number "1" in the record-card punching operation, the return movement of the lever 360 then re-setting the unit for the number of the next succeeding card

so punched, as card number "2," etc. Moreover, as shown in the present example and at best appears in Fig. 1, the recorder card-punching mechanism may include additional, adjustably fixed punch elements, as the punch elements 460 arranged in four vertically spaced, horizontal series of ten punches each. These punches align with the last column of indicia on the card 444, as the numbers for indicating the "Box No." of a given fare box. Thus, certain of the punches 460 according to the box number desired to be recorded on the card 444, will be pre-set in extruded positions, so that in the card punching process, the desired box number will be punched or recorded in the appropriate column of the card.

While the operator's run card 444 as illustrated by Fig. 9, discloses a total of fourteen distinct columns or record indicia or numerals, only those headed by "Cash"; "Spec. A" (transfers, from recorder unit 401); "Small tokens"; "Spec. B" (transfers, from recorder unit 403); "Large tokens"; "Card No.," and "Box No.," are acted upon in the punch device of the fare box embodiment herein described. However, the columns not punched by the presently described recorder device, may be pre-punched or otherwise suitably marked, either by hand, or by a separate punching machine adapted for the purpose. It may be noted in this connection that certain of the latter columns, as those headed by "Car No.," "Line No.," and "Run No.," may be punched in the present recorder mechanism, as by including therein, appropriate adjustably fixed punch elements therefor. Although such are not shown by the present disclosure, the additional punch assemblies may correspond to the assembly of punch elements 460 located at the bottom of the recorder mechanism (Fig. 1).

Turning now to the provision herein, for resetting the several punch assemblies, with the exception of the punch unit 405 which is controlled from the hand lever 360 in the manner hereinbefore described, it will have appeared that, since the recording units 400, 402, 404, 401 and 403 are actuated by connections operating through unit ratio, as driven respectively, from the associated coin- and token-responsive shafts 292, 316 and 332, and the transfer counter-actuated shafts 388 and 388A, a suitable independent drive may be provided for each unit, to effect resetting thereof to zero recording position. Accordingly, it is proposed to employ the single manual operation of resetting the per-man counters by actuation of the hand lever 360, as such counter resetting function of the hand lever 360 is fully disclosed in the application Serial No. 312,012, hereinbefore noted, to also reset and clear the recording units 400—404.

The recorder resetting mechanism which best appears in Figs. 2, 6 and 7, will be described in detail, in connection with the larger or cash recorder unit 400 only, since the resetting mechanisms for the other units 401—404, are but duplicates thereof. However, the corresponding reset elements of the latter devices will bear similar numerals but distinguished by different letter suffixes, after the manner of the descriptive designations of the principal parts of the several punch units hereinbefore described. Referring to the punch unit 400, each of the drum shaft 420—424 supports on the end thereof opposite its drive end, a unidirectional or ratchet type clutch device 470, one element of which is secured to the shaft end, while the mating ele-

ment is free on the shaft, and is urged into engagement with the first by a coiled spring 471. Each of the clutch elements which are free on the drum shafts, carries or has formed as a part thereof, a pinion 472. All of the pinions are rotatable in unison and in the same direction, through interconnecting gears 473, the arrangement being such that the pinion 472 on drum shaft 420 enmeshes with one of the gears 473, the latter in turn, enmeshing with the next adjacent pinion 472 on drum shaft 421; the latter pinion enmeshes with another of the gears 473 which in turn, enmeshes the next pinion on drum shaft 422, and so on to the last pinion 472 on drum shaft 424. The arrangement and operation of the several unidirectional clutches are such that during rotation of the drum shafts in the recording cycle of the recorder mechanism, the clutch pinions will not be rotated, but will be axially displaced against the loading of the clutch springs 471, to release the clutch. When, however, the several clutch pinions are driven from the resetting drive as will presently appear, and are thereby rotated in the same direction of rotation to which the drum shafts are subject, as driven from the trip counters, the clutches will become engaged to drive the drum shafts, to the end of resetting and clearing the punch actuating drum assemblies.

The recorder resetting drive to the clutch pinion 472 and gears 473, is effected in the present example, from the operating shaft 373 (Fig. 2), which is actuated in response to the return movement of the hand lever 360 as fully set forth in my application Serial No. 312,012, referred to hereinbefore. For the purpose of the present example, the operating connection between the hand lever 360 and the shaft 373, as such appears in Figs. 2, 6 and 10, may be here briefly described as comprising the gear segment 363 on the lever actuated plate 362, pinion 364 in engagement with the gear segment, unidirectional drive clutch 369, shaft 367, bevel gear 371 and bevel gear 372 enmeshing therewith and secured to shaft 373. The operative arrangement of the clutch 369 in the drive between the hand lever actuated gear segment and shaft 373, is such that as the hand lever 360 is depressed, the clutch will "ride free," so that no rotation of the reset shaft 373 will take place, but upon the return movement of the hand lever, the clutch will engage to cause rotation of the shaft 373. In the present example, the resetting drive may be effected from shaft 373 to one of the gears 473, or as presently preferred, to one of the clutch pinions 472, as the pinion 472 associated with the recorder drum shaft 421 (Figs. 2 and 6). As appears in the figures referred to, the end 474 of shaft 421, operatively supporting one element of the clutch 470 associated therewith, terminates inwardly of the adjacent end wall 475 of frame 418. Axially aligned with such shaft end and normally abutting the same, is a stub shaft 476 which is rotatively and slidably journalled in the wall 475. Secured to the inner end of the stub shaft, are the pinion 472 and mating element of clutch 471, the pinion and clutch element projecting forwardly of the stub shaft and freely journalled on the drum shaft end 474. The opposite end of the stub shaft is projected outwardly beyond the frame wall 475, to receive an elongated hub 477 of a bevelled gear 478, the latter as shown (Fig. 2), enmeshing with a similar bevelled gear 479 secured to shaft 373. The gear hub 477 is slotted in the axial direction, as at 480, and receives

therein a pin 481 secured to and projecting transversely of the stub shaft, the pin and slot connection thus serving to operatively connect the stub shaft and gear 478 for conjoint rotation, and to permit axial displacement of the stub shaft relative to the gear 478. The latter provision enables resetting drive disconnection at the clutch 471, during counter actuation of the recorder, as will now readily appear. Accordingly, it will be now appreciated that the recorder reset connections are such that, upon return or reset movement of the hand lever 360, the punch units will be restored to a position wherein the zero punches are held extended. Thus a card may be punched at the beginning of a trip or run to indicate a cleared machine.

The operation of the punching units has been described in connection with the description of elements thereof, and is necessarily thought to be fully apparent. Essentially these units will follow the corresponding counters in operation so as to provide by inserting and punching a card, a permanent record of the data visibly ascertainable at any time from the per-man cash and token counters 273, 274 and 275, and from the transfer counters 276 and 277. It will further appear that the counters proper may be omitted in case their use is not necessary, and that the recording mechanism, including the punching units and the drive elements thereof may be utilized entirely independently of the counters, as a complete and operative agency.

The recorder mechanism as described hereinabove, is adapted for producing a record of the totals accumulated by the machine, by a card punching process, employing for this purpose punch elements 430 of the form best appearing in Figs. 1, 5 and 12. As before indicated and as will now appear, the recorder may be adapted readily and easily, for the production of a printed record of the totals upon a suitable record card provided therefor. The only changes necessary in the recorder mechanism as described for card-punching operation, reside in the adaptation of the several punch elements 430, 430A, etc., for card-printing, and in the provision of an inked printing ribbon or tape and actuating mechanism therefor. In all other respects, the recorder mechanism and the apparatus for presenting a record card to the record producing punches thereof, may be substantially the same in each case. Accordingly, the corresponding but unchanged elements of the recorder as adapted for a card-printing function, will bear the same reference numerals applied to the card-punching recorder.

The recorder as modified in the above respects, is illustrated by Fig. 13, wherein all of the card-punching elements 430, 430A, etc., of the several units 400, 400A, etc., are now replaced by similar elements 500, 500A, etc., each of which has formed on its card-engaging end a suitable, raised printing indicia or numeral. One of these elements or printing dies is illustrated in perspective, by Fig. 14, and bears the numeral "2" on the printing end face thereof. The card-well forming plates 501 and 502 corresponding to the plates 440 and 441 as described for the punching recorder, differ therefrom only in that the plate 501 is imperforate, to provide an unbroken back or printing platen for a record card, while the plate 502 is changed in respect to the corresponding plate 441 only as to the provision of a ribbon or tape receiving slot 502A in its upper end.

Secured to and projecting inwardly from the upper end of the frame wall 368, is a bracket 503,

upon which is rotatively mounted in a readily removable manner, a spool 504 supporting a roll of printing ribbon or tape 505. The spool is retarded or "braked" in its rotation, by a suitable leaf-spring element 508 in engagement with a peripheral portion of the latter. The printing tape is extended upwardly from the spool-roll, through a slot 507 provided therefor in frame wall 368, through the slot 502A in card plate 502, and thence downwardly between the plates 501—502 and over the inner face of the latter. The lower end of the tape is then carried over a suitable guide roller 508 and through a slot 509 in wall 368, to a tape-receiving or wind-up spool 510 rotatably supported by a bracket 511. In order to present a clean section of the tape for each card-printing operation of the recorder, the wind-up spool 510 may be driven from the recorder mechanism in a manner such that the tape will be displaced upon the actuation of the recorder to set up the printing elements thereof. For this purpose, there is operatively secured to the lower spool 510, a gear element 512 which enmeshes with an intermediate or idler gear 513, the latter in turn enmeshing with a drive gear 514 on say, the drum drive shaft 420E of the lower plunger unit 405. Thus the wind-up spool is driven from the recorder unit 405, to effect the desired displacement of the printing tape 505 for the purpose indicated.

The card-printing operation of the printing recorder is believed to be now fully apparent, so that no detailed description thereof is needed, except to point out that the record-card when inserted in the recorder well, will be behind the tape, such that when the card is urged against the extruded printing elements or dies, the latter will bear against the tape to imprint the legends or numerals of the dies upon the card.

A further modification may be made in the card-punching recorder mechanism hereinbefore described, in respect to additional printing mechanism for collecting and printing the totals accumulated on the recorder, say at the top of the respective card-columns punched by the recorder punches. The modified structure to accomplish the above purpose, is shown by Figs. 15 through 18, and as before, the elements of the recorder disclosed therein, which remain unaltered over the corresponding elements of the recorder as heretofore described, are designated by the same reference characters applied to the latter. Moreover, the present description will be confined to the large unit 400, since the printing arrangements for the other units 401—404 are similar.

Each of the drum shafts 420, 421, 422 and 423 (the shaft 424, its drum and coacting punch assembly being omitted in the present example) is provided on the end thereof to which the recorder resetting drive is connected, with a bevelled pinion 520. A similar bevelled pinion 521 enmeshes with the pinion 520, and associated in driven relation with pinion 521, as through intermediate or idler gears 523, is a gear 524 connected to a numeral-bearing disc or drum 525. The drum 526 which bears raised numerals from 0 to 9 equally spaced about its periphery, is located at the card-punching end of the recorder and projects forwardly therein, through an aperture provided therefor in the frame wall 368. As appears in Fig. 15, there are four such numeral discs, arranged in vertically spaced, horizontal superposed relation, one thereof for each of the drum shafts 420—423. Card locating plates 526 and 527 supported and actuated in the same manner as the

corresponding plates 440—441 heretofore described, are modified over the latter, in that the inner plate 527 along one vertical end thereof, is apertured, as at 528, to receive therethrough, the numeral discs above described. The outer plate 526 is provided with blocks or pads 529 of rubber or other resilient material, in register with the plate apertures 528. These elements 529 serve as a soft backing for the portions of the record card to be printed by the numeral discs, as will readily appear. A printing ribbon or tape 530 is included in the printing assembly, arranged so as to lie between the numeral discs and the card to be printed thereby, in the printing process. The printing ribbon here employed, may be mounted and actuated substantially as described for the printing ribbon 505 of the printing-recorder illustrated by Fig. 13.

The arrangement of the totals printing mechanism as now described, is such that the totals accumulated by the recorder, will be set up on the numeral discs in a manner readily apparent. Thus in the card-punching and printing process, the totals will be printed on the card in spaces provided therefor, at the head of the several columns, as appears at 531 on the record-face of the card shown by Fig. 19.

A further modification appears in the recorder embodiment under present discussion, in respect to the card-punching elements 430, 430A, etc., of the several recorder units 400—405. These elements as here shown, are modified to provide round card-punching ends 532, which in the card-punching operation, are received in correspondingly round apertures 533 in the card-locating plates 526 and 527. Also, the several punches are biased or urged to retracted or initial positions, by return springs 534, a provision which may be included, if desired, in the punch assemblies 430, 430A, etc., of the principal embodiment of the recorder heretofore described.

It is to be noted here in connection with the printing discs 525, 525A, etc., as driven from the drum shafts of the recorder units 400, 401, etc., that the operation of resetting and clearing the recorder mechanism, will serve at the same time, to reset the printing discs to zero reading, as will now be obvious.

While the invention has been described my making specific reference to presently selected embodiments thereof, the detail of the description is to be understood solely in an illustrative and not in a limiting sense, since numerous changes may be made in the parts and the combinations of elements embodied in the structure, without departing from the spirit of the invention and the full intended scope of the claims hereunto appended.

I claim as my invention:

1. In a recording device of the character described, a rotary drum movable from an initial position, a plurality of projections on said drum, a plurality of punches or alternately printing elements arranged for actuation from initial positions into recording positions by said projections, drive means for said drum, means for deriving a record from said punches or alternately printing elements in recording positions, actuating means for said record deriving means, and means controlled by said actuating means and operable independently of said drive means for returning the drum to said initial position.

2. In a recording device of the character described, a rotary drum movable from an initial position, a plurality of projections on said drum,

a plurality of punch or alternately printing elements arranged adjacent said drum for actuation from initial positions into recording positions by said projections, the projections being angularly and axially spaced from each other so that each thereof actuates one of said elements, drive means for said drum, means for deriving a record from said elements in recording positions, actuating means for said record deriving means, and means actuated from said actuating means during a portion of its operation and operable independently of said drive means, for returning the drum to said initial position.

3. A recording device of the character described including a rotary member movable from an initial position, a plurality of projections on said member, a plurality of punch or alternately printing elements arranged for actuation into recording positions by the projections, drive means for the rotary member, means for deriving a record from said elements in recording positions, including a holder for a record sheet and camming means for effecting movement of said holder and record sheet therein toward said elements, operating means independent of said drive means for actuating said camming means, and means including a unidirectional clutch device, arranged between said operating means and said rotary member, and operable by said operating means during a portion of its operation, for returning said rotary member to its initial position.

4. In a recording device of the character described, a rotary member movable from an initial position, a plurality of projections on said member, a plurality of punch or alternately printing elements arranged adjacent said member for actuation into extended positions by the projections, the projections being so spaced in relation to said elements that each thereof engages one element and being spaced to actuate the elements individually, drive means for said rotary member, a ratchet device associated with said member for releasably retaining the member in a position wherein one of said elements is held by its associated projection in extended position, means for deriving a record from said elements in recording positions, operating means independent of said drive means for actuating said record deriving means, and means actuated from said operating means during a portion of its operation, for returning said member to its initial position.

5. In a recording device of the character described, a plurality of punches arranged in superposed rows, a plurality of drums one for each of said punch rows and each drum being rotatable from an initial position, projections on each drum, angularly and axially spaced from each other so that each projection is positioned for engagement with one of said punches in a given row, whereby said punches are extended one at a time upon rotation of the associated drum, means connecting one drum to be driven in a given ratio by the next preceding drum constituting a driving element therefor, drive means for determining the extent of actuation of the driving element, means for deriving a record of the positions of said punches, actuating means independent of said drive means for operating said record deriving means, and means operated from said actuating means for returning said drums to their initial positions.

6. In a recording device of the character described, a plurality of punches arranged in superimposed rows, a plurality of drums one for each of said punch rows and each rotatable from an

initial position, said drums being spaced with their axes one above another and laterally spaced from each other, a plurality of punch-actuating projections on each drum, angularly and axially spaced from each other so that each projection is operatively associated with one punch of a given row and such that the punches are actuated one at a time thereby upon rotation of the associated drum, means operatively connecting said drums to drive one drum in a given ratio by the next preceding drum constituting a driving element therefor, drive means for determining the extent of actuation of the driving element, means for deriving a record of the positions of said punches, actuating means independent of said drive means for operating said record deriving means and means including a unidirectional clutch connecting said actuating means to said drums, operable by said actuating means during a portion of its operation, for restoring said drums to their initial positions.

7. In combination with a recording device of the character described, providing a plurality of punches and means for selectively actuating said punches into recording positions, means for deriving a record of the positions of said punches, comprising a pair of movable plates spaced to receive a record sheet therebetween, at least one of said plates being apertured to receive the ends of said punches, camming means operable initially to move one of said plates toward the other, and thence to move both plates toward said punches, and actuating means for said camming means.

8. In combination with a recording device of the character described, providing a plurality of punches and means movable from an initial position, for selectively actuating said punches into recording positions, means for deriving a record of the positions of said punches, comprising a pair of movable plates spaced to receive a record sheet therebetween, at least one of said plates being apertured to receive the ends of said punches, camming means operable initially to move one of said plates toward the other, and thence to move both plates toward said punches, actuating means for said camming means, and mechanism operable by said actuating means, adapted for returning said punch actuating means to its initial position.

9. The combination with a recording device of the character described, providing a plurality of printing elements and means for selectively actuating said elements into printing positions, of means for deriving a printed record from said elements, a pair of movable plates spaced to receive a record sheet therebetween, one of said plates being apertured to receive the printing ends of said printing elements, camming means operable initially, to move one of said plates relative to the other, and thence to move both plates toward said elements, and a printing ribbon extending between said plates, in a position to overlie the printing field of the record sheet.

10. In combination with a recording device of the character described, providing a plurality of printing elements and means movable from an initial position, for selectively actuating said elements into printing positions, means for deriving a printed record from said plunger, comprising a pair of movable plates spaced to receive a record sheet therebetween, one of said plates being apertured to receive the printing ends of said elements, camming means operable initially, to move one of said plates relative to the other, and

thence to move both plates toward said elements, an actuating device for said camming means, a printing ribbon extending between said plates, in a position to overlie the printing field of the record sheet, means for advancing said printing ribbon, and mechanism operable for returning said printing element actuating means to initial position, said ribbon advancing means and said return mechanism being operated from said actuating device.

11. In a recording device of the character described, a rotary drum movable from an initial position, a plurality of projections on said drum, a plurality of plungers arranged for actuation into recording positions by said projections, means for operating said drum, a totals accumulator mechanism including record producing elements operable from an initial position, responsive to rotary movement of the drum, means for deriving a record of the positions of said plungers and a record from said elements of the accumulator mechanism, actuating means for said record deriving means, and means operated by said actuating means, for returning said drum and the record producing elements of said accumulator mechanism to their initial positions.

12. In a recording device of the character described, a rotary member movable from an initial position, a plurality of projections on said member, a plurality of punch or alternately printing elements selectively operable from initial positions into recording positions by said projections, a support common to said elements and formed to provide guides therefor, means on said support and cooperating with each of said elements to limit the movement thereof, drive means for said rotary member, and means operable independently of said drive means, for returning said member to its initial position.

13. The combination with a recording device of the character described, providing a plurality of punch or alternately printing elements and means for selectively actuating said elements into recording positions, of means for deriving a record of the positions of said elements, comprising a pair of movable plates at least one thereof being apertured to receive the ends of said elements, yieldable means normally positioning said plates in spaced relation for the reception of a record sheet therebetween, camming means operable initially to move one of said plates toward the other, and thence to move both plates toward said elements, and actuating means for said camming means.

14. In a recorder of the character described, a rotatable member, drive means for said member, a plurality of record producing elements movable into recording positions in substantially a common plane, means actuated by said member for moving said elements into recording positions, record deriving means including a pair of movable plates arranged substantially parallel to said plane and spaced to receive a record sheet therebetween, camming means operable initially to move one of said plates toward the other, and then to move both plates and the record sheet therebetween toward said plane, whereby to effect a record on said record sheet from the record producing elements in recording positions in said common plane, and operating means independent of said drive means for actuating said camming means.

15. In a recorder of the character described, a rotatable member, drive means for said member, a plurality of record producing elements mov-

able into recording positions, means actuated by said member for moving said elements into recording positions, record deriving means comprising a pair of movable plates, supporting means for said plates including resilient elements normally positioning said plates in relatively spaced relation for receiving a record sheet therebetween, camming means operable initially to move one of said plates toward the other to clamp the record sheet therebetween, and thence to move both plates and the record sheet toward said record producing elements, whereby to effect a record on said sheet from the record producing elements in recording positions, and operating means independent of said drive means for actuating said camming means.

16. In a recorder of the character described, a shaft rotatable from an initial position, drive means for said shaft, a plurality of record producing elements, means operated responsively to rotation of said shaft for actuating said record producing elements into recording positions, record deriving means comprising a pair of movable plates spaced to receive a record sheet therebetween, camming means operable initially to move one of said plates toward the other, and thence to move both plates and the record sheet therebetween toward said record producing elements, whereby to derive a record on said record sheet from the record producing elements actuated into recording positions, operating means for said camming means, and means actuated by said operating means for effecting return of said rotatable shaft to its initial position.

17. In a recorder of the character described, a shaft rotatable from an initial position, drive means for said shaft, a plurality of record producing elements, means operated responsively to rotation of said shaft for actuating said elements into recording positions, record deriving means comprising a pair of movable plates spaced to receive a record sheet therebetween, camming means operable initially to move one of said plates toward the other and thence to move both plates and the record sheet therebetween toward said record producing elements, whereby to derive a record on said sheet from the elements

actuated into recording positions, actuating means movable from an initial position for actuating said camming means to effect said movements of said plates, and means operated by said actuating means upon return movement thereof to its initial position, for effecting return of said rotatable shaft to its initial position.

18. In a recorder of the character described, a plurality of shafts each rotatable from an initial position, differential drive means interconnecting said shafts to effect rotation of one shaft in a given ratio by the next preceding shaft, means for determining the extent of differential actuation of said shafts, a plurality of record producing elements, means operated responsively to rotation of said shafts for actuating said record producing elements into recording positions, record deriving means comprising a pair of movable plates spaced to receive a record sheet therebetween, camming means operable initially to move one plate toward the other, and thence to move both plates and the record sheet therebetween toward said record producing elements, whereby to derive a record on said sheet from the record producing elements actuated into recording positions, operating means for said camming means, and means actuated by said operating means for effecting return of said shafts each to its initial position.

19. In a recording device of the character described, a rotary drum movable from an initial position, a plurality of projections on said drum, a plurality of punches arranged for actuation into recording positions by said projections, drive means for said drum, a totals accumulator mechanism including record producing elements operable from an initial position by rotary movement of said drum, means for deriving a record on a single record sheet, from said punches in recording positions and from said elements of the accumulator mechanism, actuating means independent of said drive means for operating said record deriving means, and means operated by said actuating means for returning said drum and the record producing elements of said accumulator mechanism to their initial positions.

FOUNT F. DAUGHERTY.
